ROTATABLE RACK FOR CONDIMENTS OR THE LIKE

Marianne Wilson Lockhart, 416 Hawthorne Ave.,
Birmingham, Mich.

Filed Oct. 1, 1965, Ser. No. 87,274

Term of patent 14 years

(Cl. D44—29)

FIG. 1

FIG. 2

FIG. 1 is a top plan view of a rotatable rack for condiment containers or the like, showing my new design;

FIG. 2 is a bottom plan view; and

FIG. 3 is a sectional view taken on the line 3—3 of FIG. 1.

I claim:

The ornamental design for a rotatable rack for condiment containers or the like, as shown.
